CLAIM

The ornamental design for a rear strap for a hoof boot, as shown and described.

DESCRIPTION

FIG. 1 is a perspective view of a rear strap for a hoof boot showing the new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a perspective view of the rear strap for a hoof boot, shown in an environment of use.

The broken lines showing a hoof boot in FIG. 8 depict environmental structure that forms no part of the claimed design.

1 Claim, 5 Drawing Sheets
